TO STRAUSE GAS IRON CO., OF PHILADELPHIA, PENNSYLVANIA, A CORPORATION
OF PENNSYLVANIA.

BUNSEN BURNER.

1,112,862.

Specification of Letters Patent. Patented Oct. 6, 1914.

Application filed April 18, 1913. Serial No. 761,898.

To all whom it may concern:

Be it known that we, OTTO SPAHR and LOUIS J. STRAUSE, both citizens of the United States, and residents of Philadelphia, county of Philadelphia, State of Pennsylvania, have invented a certain new and useful Improvement in Bunsen Burners, of which the following is a specification.

Our invention relates to Bunsen burners more particularly of the type used in connection with self-heating gas irons and the like, and has for its object to construct such burners in a manner to adapt them for any gas pressure and supply, and to prevent meddling, disarrangement, and incorrect adjustment of the parts by uninstructed persons.

Other objects of our improvement will appear from the description hereinafter, and the features of novelty will be pointed out in the appended claims.

Reference is to be had to the accompanying drawings in which—

Figure 1 is a side elevation, greatly enlarged, of our improved Bunsen burner; Fig. 2 is a central longitudinal section thereof; Figs. 3 and 4 are fragmentary sectional views showing the parts in different positions, and Fig. 5 is a view similar to Fig. 4 showing a different form of our improvement.

As shown in the drawings, our invention comprises a body 5 having an annular flange 6 at its one end and an exteriorly screw-threaded nipple 7 projecting therefrom, said nipple 7 terminating in a pointed or conical end 8. A passage 9 extends axially through said body 5 and nipple 7 and has its inner end preferably tapering and in communication with a needle opening 10 located at the apex of the conical or pointed end 8 as shown, for instance, in Fig. 2 of the drawings. One or more additional openings 11 extend transversely through the wall of the conical end 8 into connection with the tapering end of said passage 9 for the purpose to be more fully described hereinafter. An air hood, which in the illustration comprises an internally screw-threaded portion 12 and a tapering portion 13 is secured to or forms an integral part of an internally screw-threaded collar 14 adapted to be screwed upon the nipple 7, into engagement with the one surface of said flange 6 whereby said air-hood is supported in operative position.

A rotatable or otherwise movable shutter 15 is mounted on the tapering portion 13 of the air hood and is provided with apertures 16 adapted to be brought into and out of registry with similar apertures 17 formed in the tapering portion 13 and communicating with the interior of the air hood as clearly shown in Fig. 2. In order that the shutter 15 may be retained in an adjusted position and held against accidental movement, a coil spring 18 may be provided, said spring surrounding the collar 14 and having its one end in engagement with the flange 6 and its other end in engagement with said shutter and serving by means of its tension to hold the shutter 15 firmly in position and yet permitting it to be readily adjusted as may be found necessary. The air hood is formed with an internal shoulder 19 and a wall 20 extending therefrom and spaced from the nipple 7 whereby an annular space 21 is formed between said nipple 7 and wall 20 when the parts are assembled. An internally screw-threaded cap 22 is adapted to screw upon the nipple 7 and into said annular space 21 and is formed with an internal chamber 23 having an inclined inner surface, the angle of inclination of which is preferably different from that of the conical end 8, said cap 22 being adapted to fit said conical end 8 and the chamber 23 having a gas outlet 24 in axial alignment with and preferably of slightly larger diameter than the needle opening 10. It will be seen that the cap 22 is adjustable on the nipple 7 for the purpose to be more fully described hereinafter, and in the illustration is maintained in an adjusted position by means of a spring 25 which surrounds the nipple 7 and with one end bears against the shoulder 19 and with its other end against the cap 22.

In assembling the burner the air hood with the shutter 15 and spring 18 thereon is secured in operative position by screwing the collar 14 upon the nipple 7 until said collar is firmly seated against the flange 6. The spring 25 is now placed over the nipple 7 after which the cap 22 is secured on said neck and the entire burner is combined, for instance, with a gas iron by simply screwing the portion 12 of the air hood upon the usual fuel inlet tube thereof. The burner may now be connected with a source of fuel supply by inserting the body 5 into the cus-

tomary flexible tube used for this purpose, the flange 6 serving to limit the inward movement of said body 5 into the end of the flexible tube. When the cap 22 is 5 screwed all the way up on the nipple 7 as shown in Fig. 2, the apex of the conical end 8 will extend through the gas outlet 24 whereby the latter is completely closed and the transverse opening or openings thus 10 sealed so that any gas or other fuel entering the passage 9 can only escape through the needle opening 10 and gas outlet 24. Under these conditions the gas or other fuel will pass into the interior of the air hood which 15 may be termed a mixing chamber at the initial pressure of the fuel supply to the apparatus and will become mixed with air entering said mixing chamber through the openings 16 and 17, the shutter being adjusted to regulate the amount of incoming 20 air necessary to secure the proper proportions. If it is found that with the described adjustment of the parts the working is not satisfactory and not suited to the particular 25 fuel pressure the cap 22 may be adjusted so as to move the end 8 out of the gas outlet 24 and leave a space between the wall of the chamber 23 and the outer surface of the conical end 8 as shown in Fig. 3 of the drawings. In this condition of the parts the gas 30 or other fuel will pass through the needle opening 10 as before and also through the transverse openings 11 into the space between the walls of the cap 22 and conical 35 end 8, from which space the gas or other fuel will pass through the gas outlet 24 to the interior of the air hood or in other words, to the mixing chamber, where it becomes mixed with air entering through the openings 16 and 17. With this adjustment the 40 gas or other fuel escapes through the outlet 24 in a slightly increased quantity and at a pressure somewhat lower than the initial pressure of the gas supply owing to the 45 fact that the combined area of the openings 10 and 11 is larger than the space between the cap 22 and conical end 8. If, however, the cap 22 is brought to the position shown 50 in Fig. 4 and so as to leave an enlarged 55 chamber beyond the conical end 8, in which chamber the gas or other fuel will be received and collected at full pressure through the openings 10 and 11 the said gas or other fuel will escape through the gas outlet 24 to the mixing chamber at substantially such 60 full pressure and in larger quantities than before. Thus the burner may be adapted for various kinds of fuel and for different pressures by simply adjusting the cap 22 as 65 described, which adjustment may be accomplished in any suitable manner but is preferably brought about by means of a suitable instrument introduced through the openings 16 and 17 and used as a lever to turn said 65 cap 22 as shown in dotted lines in Fig. 2,

the said cap being preferably provided with a milled or otherwise roughened portion 22^a to facilitate this operation. To permit of a ready insertion of the said instrument one or more of the openings 16 and 17 may 70 be enlarged or may be of any shape best suited for the purpose. Owing to the fact that this operation would not be explained to an ordinary user of an apparatus including our improved device the same 75 owing to its construction would be free from the danger of tampering and disarrangement by unskilled persons, and would be properly adjusted by an expert operator. Such expert operator would set the cap 22 80 and adjust the air shutter in exact compliance with the requirements of any particular locality, for instance, different cities in which the pressure at which the gas is delivered, differs and in which even the 85 quality of gas is different. Heretofore in gas irons or other apparatus which include Bunsen burners of existing types, the adjusting means for adapting said burners to different local gas conditions has generally 90 been so located or exposed as to be readily tampered with or accidentally disarranged whereby the intended adjustment was changed and the burner consequently rendered more or less defective in operation 95 and result. With our invention this is entirely avoided and each burner may be easily adjusted to all the different pressures at which local gas or the like may be used, and when once adjusted cannot be disarranged by accident or otherwise and can only be readjusted when desired. 100

In the form of our improvement shown in Fig. 5, the nipple 7 is provided with a reduced neck 7^a terminating in a pointed or conical end 8^a similar to the end 8 of the first form of our invention. The said neck 7^a is externally screw-threaded to accommodate a cap 22^a similar to the cap 22 and provided at its one end preferably with an annular flange 22^b or other projection, the purpose of which will appear presently. In this form of our improvement the air hood is formed with an internal shoulder 21^a located in the annular chamber 21 which shoulder 21^a in coöperation with the annular flange 22^b serves to prevent a complete removal of the cap 22^a from the neck 7^a when said cap is actuated for purposes of 110 adjustment. In all other respects this latter form of our improvement as well as its method of operation may be the same as in the first form of our invention. With this latter form of our invention it will be seen that it is impossible to completely separate 115 the cap 22^a from the neck 7^a when the parts are assembled so that accidental or other dislocation of said cap is prevented without interfering with the actuation or functions thereof. In assembling this form of our im- 120 125 130

5 provement, the cap 22^a is first screwed upon the neck 7^a after which the air hood is placed in operative position by connecting the collar 14 with the upper portion of the nipple 7.

Various changes in the specific form shown and described may be made within the scope of the claims without departing from the spirit of our invention.

10 We claim:

1. In a Bunsen burner, a device adapted for connection with a fuel conducting tube, an apertured air hood detachably connected with said device, an adjustable air regulating shutter on said air hood, means for maintaining said shutter in an adjusted position, a nipple connected with said device and extending into said air hood, a cap adjustable relatively to said nipple for regulating the fuel pressure and supply in said air hood and means for maintaining said cap in an adjusted position.

2. In a Bunsen burner having a mixing chamber, a conical nipple having a continuously open outlet aperture at its apex, and additional outlet openings located adjacent to said apex, and extending at right angles to the axis of the nipple, and a cap having an outlet leading to said mixing chamber, said cap being adjustable relatively to said nipple whereby said additional openings are opened or closed and the outlet of said cap is moved toward or away from said conical nipple.

3. In a Bunsen burner, a device adapted for connection with a fuel conducting tube, an apertured air hood detachably connected with said device, an internal flange in said air hood, a nipple connected with said device and extending into said air hood, a cap adjustable on said nipple for regulating the fuel pressure and supply in said air hood, a projection on said cap adapted to coöperate with said flange for preventing said cap from being disconnected from the nipple and a spring engaging said cap and exerting a force tending to move said projection toward said flange and adapted to maintain said cap in an adjusted position.

4. In a Bunsen burner having a tubular mixing chamber and air inlets leading thereto, a movable tubular shutter extending over said mixing chamber and having apertures adapted to be brought into and out of registry with said air inlets whereby the supply of air to the mixing chamber may be regulated, a shoulder on said burner and a spring having its one end in engagement with said

shoulder and its other end in engagement with one end of said shutter and arranged to maintain said shutter in an adjusted position.

5. In a Bunsen burner, a mixing chamber, a fuel inlet connected therewith and tapering toward its exit end, said fuel inlet being provided with an axial opening and with transverse openings, and a cap on said inlet provided with an axial opening adapted to communicate with said transverse openings and adjustable to regulate the pressure and supply of fuel in said mixing chamber, said cap being inclined interiorly at an angle differing from the angle of the taper of said fuel inlet.

6. In a Bunsen burner having a mixing chamber and air inlets leading thereto, a movable shutter having apertures adapted to be brought into and out of registry with said air inlets, a shoulder on said burner, a spring having its one end in engagement with said shutter for maintaining said shutter in an adjusted position, an externally screw-threaded fuel inlet leading to said mixing chamber, an internally screw threaded cap arranged to screw on said fuel inlet for regulating the fuel pressure and supply in said mixing chamber, and a spring engaging said cap and adapted to maintain it in an adjusted position.

7. In a Bunsen burner having an air hood, a fuel inlet leading to said air hood, a cap adjustably mounted on said fuel inlet and adapted to regulate the pressure and supply of the fuel in and to the air hood and co-operating means located respectively on said cap and air hood for preventing said cap from being disconnected from said fuel inlet.

8. In a Bunsen burner having an air hood, a fuel inlet leading to said air hood, a cap adjustably mounted on said fuel inlet and adapted to regulate the pressure and supply of the fuel in and to the air hood, a projection on said cap and an internal projection in said hood adjacent to said cap adapted to coöperate with the first named projection to prevent said cap from being disconnected from said fuel inlet.

In testimony whereof we have hereunto set our hands in the presence of two subscribing witnesses.
